UNITED STATES PATENT OFFICE.

JOHANNES CHRISTIAAN WEGERIF, OF LEIGH-ON-SEA, ENGLAND.

ROLLER-MILL FOR GRINDING AND CRUSHING.

SPECIFICATION forming part of Letters Patent No. 674,718, dated May 21, 1901.

Application filed September 6, 1900. Serial No. 29,181. (No model.)

To all whom it may concern:

Be it known that I, JOHANNES CHRISTIAAN WEGERIF, civil engineer, of Leigh-on-Sea, in the county of Essex, England, have invented 5 new and useful Improvements in Roller-Mills for Grinding and Crushing, (for which an application for a patent has been filed in Great Britain, dated January 11, 1900, No. 662,) of which the following is a full, clear, and exact 10 description.

My invention relates to improvements in hyperboloidal roller-mills for crushing and grinding, in which the axes of the rolls cross or lie in planes oblique to the one to the other, 15 so that the planes of rotation of the rolls are oblique to each other, and consequently the particles passing between the grinding-faces of the rolls are subjected to a tearing or disruptive action. With the ordinary hyperbo- 20 loidal rolls this obliquity of the roll-axes involves one or both axes being situated out of the horizontal plane, in consequence whereof an undue proportion of the pressure comes upon the bearing at the lower end of the roll, 25 thereby very seriously affecting the efficiency of such rolls. My invention obviates this evil, the axes of both rolls being perfectly horizontal, which gives yet another advan- 30 tage in that it enables the rolls to be mount- ed in the way most suitable in practical mill- work, as more fully described hereinafter.

In order to obtain the maximum efficiency, it is essential that the crushing-rolls be pressed together not only with a mere downward pres- 35 sure directly proportional to the load, but with an increased pressure, due to a wedge-like action of the upper roll consequent on the axis of that roll being constrained to remain in a different vertical plane from that in which 40 the axis of the other roll is situated. With rolls thus partly superposed the one above the other the direction in which the material to be crushed enters between the rolls is more or less approaching the horizontal and should 45 be wholly in a downwardly-inclined direction, and in order to insure an even distribution of the material along the line of contact or "bite" it is essential that this line of contact or bite of the rolls should itself be as nearly horizon- 50 tal as is possible, so as to avoid interfering

with the disruptive action set up by the hyperboloidal rolls in order that the material may not tend to gravitate toward one end.

It is the object of this invention to produce a machine in which these features are com- 55 bined. In the case of rolls whose axes are oblique to one another and whose acting sur- faces are consequently of concave hyperbo- 60 loidal configuration it is necessary in order to prevent undue pressure on the bearings, 65 with its attendant heating, loss of power by friction, &c., that the axes of both rolls should always be in horizontal planes. A mill so constructed is illustrated in the accompan- 70 ing drawings, wherein—

Figure 1 is a diagram of a pair of rolls, illus- 75 trating in a highly-exaggerated manner a pair of crossed rolls of truncated concavo-conoidal form according to my invention, the feed side of the rolls being supposed to be at the side 80 farthest from the observer. Fig. 2 is a dia- 70 grammatic elevation and plan view of the rolls as used in the mill illustrated, except that the actual concavity of the roll-faces, being so slight as to be hardly perceptible, is 75 not apparent in this figure in consequence of the reduced scale and the shortness of the rolls. Fig. 3 is a side elevation, Fig. 4 a plan, and Fig. 5 a front elevation, of the mill, the driving-pulleys being omitted in Figs. 3 80 and 5. Fig. 6 is a part side elevation show- 85 ing the pressure-lever and upper roll thrown back. Fig. 7 is a horizontal section and end elevation of one of the thrust-bearings.

A is the upper roll and B the lower roll, *a a* 85 in Figs. 1 and 2 being the axis of the upper roll and *b b* the axis of the lower roll, the two axes lying in different horizontal and dif- 90 ferent vertical planes, the vertical planes being oblique to each other.

x x, Figs. 1 and 2, represent the line of 95 contact or bite of the two rolls, this line being by reason of the conicity and concavity of the rolls both a straight and a substantially horizontal line.

The means of mounting the rolls consists, essentially, in journaling the upper or pres- 100 sure roll A in a single frame C, adapted to act as a pressure-lever, the said lever being composed of two side members *c c*, cast in one,

together with a cross-bracing c' . The lever C is fulcrumed, preferably, on two alined fulcrum-pins D D, the width between the members c c , and consequently the width of bearing between the pins D, being so much greater than the length of the roll A as to prevent all lateral tilting action of the said roll, which might otherwise ensue in consequence of an excess of material being fed in toward the one or the other end of the roll. Lateral play of the lever is prevented by the ends of the members c of the lever C being received in forked bearings E, which carry the fulcrum-pins D, the said bearings being each carried by bolts F, which are anchored to the cheeks of the main frame G of the machine, or the bearings E might be otherwise suitably supported so as to resist the strain due to the wedge-like action of the roll A. The two side members c of the lever-frame C converge symmetrically to a point c^2 to form the long arm of the lever, to which point the pressure (which may be spring, hydraulic, or other) is applied. The pressure being thus applied at a single point will necessarily be equally divided between the two ends of the roll, the end of the lever being suitably guided. The pressure is shown as being applied by helical springs S, confined between an adjustable fixed head s and a movable head s' , applied upon the end of the lever C, both heads being on a guide-rod T, anchored at t to the frame G, and upon which the forked end c^3 of the lever C plays and by which it is guided, the lever in its lowest position resting on packing-blocks t^2 . In consequence of the lateral disruptive action due to the mutual obliquity of the planes of rotation of the two rolls there will be a lateral thrust of the rolls in opposite directions, to resist which the one journal of each roll is provided with a thrust-bearing H, as shown in Fig. 7, wherein h is a circle of balls rolling in circular grooved paths in the end of the roll-journal and in a thrust-block H, adjustable by means of a screw H' , working in a threaded cap bolted to the outer end of the journal-bearing.

The lower roll B is driven by a belt on a pulley I, and the upper roll A is driven by a rope band running on a grooved pulley J, (or a belt and pulley may here be used,) these pulleys being on the gudgeons opposite to those which are provided with thrust-bearings, dust-excluders being provided for the bearings both at the inside and outside of the bearings.

The material is fed to the rolls A B by a hopper K, having its side cheeks adapted to fit over or embrace the lateral faces of the rolls, notwithstanding their mutual obliquity, so as to inclose at the sides the entry to the rolls up to the line of bite, the feed-hopper being made adjustable so as to fit, notwithstanding the wear of the rolls.

65 The journals of the pressure-roll A are re-

ceived and retained in capped bearings A' in the lever C, so that by raising the lever and swinging it over backward to an inverted position, as shown in Fig. 6, the lever C and the pressure-roll A will be moved wholly out 70 of the way to afford free access to the roll B below.

In the case of a three-high roll the lower one would be mounted in stationary bearings, the middle one in slide-block bearings, 75 and the upper one in a pressure-lever C, as above described.

Having now particularly described and ascertained the nature of the said invention and in what manner the same is to be performed, 80 I declare that what I claim is—

1. In a roller-mill, rolls partially superposed and having their axes lying obliquely across each other, in parallel horizontal planes and in different vertical planes, the 85 rolls being of truncated concavo-conoidal or semihyperboloidal form, and both rolls being coned toward the same side of the machine, as described.

2. In a roller-mill for grinding and crushing, rolls partially superposed one above the other, the axes of the rolls lying in vertical planes oblique to each other, and in parallel horizontal planes, the acting surface of the rolls being slightly concave, and conoidal in 95 form, the smaller ends of the rolls being at the same side of the machine and the line of bite of the rolls being substantially straight and horizontal, an adjustable feed hopper or box for feeding the material downward to the 100 line of bite, the said hopper inclosing at the sides the entry to the rolls up to the line of bite, and means for pressing the upper roll against the lower with a yielding pressure, the said pressure-roll moving in a vertical 105 plane, as set forth.

3. In a roller-mill for grinding and crushing, rolls partially superposed and having their axes lying in vertical planes oblique to each other and in parallel horizontal planes, 110 the rolls being of truncated concavo-conoidal form and both rolls being tapered toward the same side of the machine, the vertical planes in which the axes of the rolls lie crossing each other outside of the line of bite of the 115 rolls, as set forth.

4. A roller-mill for grinding and crushing, comprising two rolls partially superposed and having their axes lying in vertical planes oblique to each other and in parallel horizontal 120 planes, the grinding-faces of the rolls being slightly concave and both the rolls tapering toward the same side of the machine, one journal of each roll being provided with a thrust-bearing to resist the lateral thrust of 125 the rolls in opposite directions, as set forth.

5. A roller-mill for grinding and crushing, comprising two rolls partially superposed and having their axes lying in parallel horizontal planes and in different vertical planes oblique 130

to each other, the rolls being of concavo-conoidal form and both rolls being coned toward the same side of the machine, a thrust-bearing for one of the journals of each roll to resist the lateral thrust of the rolls in opposite directions, the said bearings each comprising an adjustable thrust-block, and balls engaging a circular grooved path in the end of the

roll-journal and in the thrust-block, as set forth.

Dated this 20th day of August, 1900.

JOHANNES CHRISTIAAN WEGERIF.
